LINE PAINTING APPARATUS

Lawrence W. Cornelison, San Francisco, Calif.,
assignor of one-half to Louise E. Cornelison,
San Francisco, Calif.

Application January 7, 1939, Serial No. 249,754

6 Claims. (Cl. 91—12)

My invention relates to line painting apparatus, and more particularly to apparatus for painting traffic markings on highways.

An object of my invention is to provide improved apparatus

(1) For automatically painting interrupted line markings;

(2) For painting interrupted line markings wherein the segments thereof follow a predetermined pattern;

(3) For enabling repainting of an interrupted line with assurance of closely matching the original;

(4) For simultaneously painting a plurality of parallel lines, periodically interrupted in accordance with a predetermined pattern;

(5) For painting interrupted line markings having sharply defined boundaries at the interruptions;

(6) For automatically providing an interrupted line of predetermined characteristics, irrespective of the rate of travel of the apparatus employed for producing such interrupted line;

(7) For providing interrupted operation of a spray gun in accordance with a predetermined sequence.

(8) Additional objects of my invention will be brought out in the following description of the same, taken in conjunction with the accompanying drawing, wherein

Fig. 1 is a side elevational view of apparatus incorporating my invention.

Fig. 2 is a plan view of a portion of the apparatus of Fig. 1, on a somewhat enlarged scale with respect to that of Fig. 1.

Fig. 3 is a view in section of control apparatus constituting an important element of the combination illustrated in Figs. 1 and 2.

The apparatus of Figs. 1 and 2 embodies the invention in the form of a novel combination, whereas the apparatus of Fig. 3, which has been referred to as the control apparatus, constitutes the construction which lends novelty to the combination.

While the invention is adapted for general application, the apparatus illustrated in the figures and which will be described herein, has been specifically designed for the painting of traffic markings on highways, and more particularly for the production of such traffic markings in the form of interrupted lines, for example, a series of line segments of similar length or differing lengths arranged in accordance with a predetermined pattern or sequence. Highway markings of this general character are more readily

perceptible and consequently more efficient in guiding traffic along highways. In addition to this advantage, an interrupted line marking enables a decided saving in paint and lacquer, such saving running in the order of 50%, depending on the relative spacing between line segments.

The combination for obtaining such results, includes as one of its elements a carriage 1 comprising a platform 3 supported upon wheels 5, and either manually or self propelled, or the same may be motivated by means of an independent automotive vehicle coupled thereto at the rear. The platform is employed to carry an air compressor 7 and an expansion tank 9 coupled thereto by means of an air line connection 11, the expansion tank in turn supplying a continuous flow of air, under pressure, to a paint tank 13 which carries the lacquer or paint employed in laying down the line markings on the highway. The compressor, if the platform is manually or self propelled, will preferably be driven from a source of primary power such as a gasoline engine 15 which is carried upon the platform and coupled to the compressor.

At the front edge of the platform, that is, looking in the direction in which the carriage 1 is to be propelled, is hingedly coupled a frame 17 of a tapering construction, and comprising a pair of side rails 19, each provided at its free end with a bearing for mounting a guide wheel 21 of any desired construction, which contacts the road surface, serving to support the frame 17 at its forward end and at the same time, enabling an operator to guide the apparatus along a predetermined path.

Intermediate the guide wheel 21 and the platform 3, and at a location somewhat closer to the guide wheel than to the platform, a spray gun 23 is mounted on the frame between the side rails thereof, the spray gun being of any type, but more particularly one in which the paint or lacquer is adapted to be atomized by air under compression, as the paint or lacquer issues from the nozzle of the spray gun, such spray gun being customarily valve operated and having a valve control lever 25 at one side thereof enabling control of the operation of the spray gun. The valve control lever 25 will normally occupy a position with the spray gun valve closed, and a stop 27 affixed to the casing of the spray gun in the path of travel of the valve lever will serve to determine the maximum movement of the lever, which in turn will determine the maximum opening of the spray gun valve.

At either side of the spray gun, and adjustably

mounted on the side rails of the frame, are line-width determining side plates 29 for limiting the lateral width of the spray issuing from the spray gun, and as a result, controlling the width of the line which is being laid down. The plates 29 are adjustably mounted, as stated, to enable such plates to be lowered into contact with the road surface, to preclude the escape of the paint or lacquer beyond the boundaries determined by the plates, and thus assuring a painted line of uniform width.

The lacquer or paint with which the line is to be painted, is conducted to the spray gun 23 from the paint tank 13, under the existing pressure of the air in the tank, such pressure resulting from the air line coupling to the paint tank from the expansion tank 9. A direct compressed air connection 31 to the spray gun from the expansion tank is also provided, such air connection 20 serving to atomize the paint as it leaves the nozzle of the spray gun.

Mounted on the frame intermediate the spray gun and the platform is the flow controlling apparatus 33, depicted on a somewhat enlarged scale 25 in Fig. 2 and on a somewhat larger scale, in section, in Fig. 3. This apparatus comprises a base 35 supported upon parallel cross members 37 interconnecting the side rails 19 of the frame 17, this base being formed to provide a guideway 39 30 parallel to the longitudinal axis of the frame.

Reciprocally mounted in the guideway 39 on the base 35 is a rack 41 which in its normal non-operating position will be located at the front end of the base. The rack is spring biased to this normal position by a pair of springs 43 interconnecting the rear end 45 of the rack to a cross member 47 spanning the guideway 39 and supported on the base member 35.

The front end of the rack is formed with an 40 upstanding perforated lug 49 adapted to receive and have bolted thereto, one end of a control rod 51, the other end of which extends through an opening in the valve control lever 25 to a point somewhat beyond such lever. The end of the 45 rod at this point is threaded and carries a coil spring 53 intermediate the control lever and a washer nut combination 55 threaded to this end of the control rod. Such spring is preferably under very slight compression tending to throw the 50 valve control lever 25 to a valve open position, but is precluded from doing this by a stop nut 57 threaded on the control rod in abutment against the valve control lever in its valve closed position and on the side opposite to that engaged by the 55 spring 53.

The base is formed with a pair of integral bearing supporting uprights 59, one to each side of the rack member guideway, and on each of these uprights, a bearing 61 is mounted. A pinion 63, affixed to a shaft 65 which is journaled in these bearings 61, is thereby supported intermediate the upright members 59 directly over the rear end portion of the rack 41 and in engageable relationship therewith. This pinion 63 is of the 60 segmented type, that is, its teeth do not extend around the entire periphery of the pinion, but are grouped at spaced intervals thereabouts, and upon rotation of the pinion in a clockwise direction (Fig. 1), such grouped teeth are adapted to engage the teeth of the rack member and retract the rack member from its normal position adjacent the front end of the base 35.

The shaft 65 to which the segmented pinion 63 is fixed, extends beyond one of the bearings 61 75 and on this extended portion of the shaft there

is provided a one way ratchet clutch mechanism. This clutch mechanism comprises a cylindrical driven member 67 affixed to the shaft by a set screw 69 or the like, and having its end surface 71 notched for engagement by the complementary driving member 73 of the clutch mechanism, such driving member having its opposing end surface 75 either notched or provided with a tooth or teeth, shaped to conform with the notches in the driven member 67. The notches and teeth are 10 substantially saw tooth in shape and directed to enable rotation of the pinion 63 in the clockwise direction as previously stated, but providing a slipping engagement when the drive through the clutch is attempted in the reverse direction. The 15 driving member 73 of the clutch is spring biased into engagement with the driven member 67 by means of a spring 77 interposed between the driving member and an enlarged end or knob 79 affixed to the end of the shaft 65. 20

A sprocket 81, integrally formed with the driving element of the clutch, enables a chain drive connection to the flow control apparatus from any suitable driving means. The driving element 73 of the clutch is further provided with a 25 peripheral groove 83 engageable by a clutch throwout mechanism in the form of a lever 85 extending rearwardly to within control of an operator and having at its clutch end a yoke or fork 87 spanning and engaging the grooved portion 30 of the driving member, the clutch throwout lever 85 being pivoted at an intermediate point 89 enabling the clutch to be manually disengaged at will of an operator. Suitable latching means 91 may be provided for retaining the lever 85 in its 35 clutch throwout position.

A chain drive connection 92 to the sprocket 81 of the flow control apparatus is established from the guide wheel 21, through a sprocket 93 affixed to the guide wheel shaft 95, which shaft extends beyond one of the frame rails 19 sufficiently to carry such sprocket. 40

In the operation of the apparatus described, the guide wheel not only performs its function of enabling the operator to guide the apparatus 45 along a predetermined path, but also serves as the driving means for the flow control apparatus. With the clutch lever in its clutch engaging position, such a drive connection will be established from the guide wheel to the control apparatus, and cause continuous rotation of the segmented pinion during travel of the guide wheel, thereby bringing about intermittent engagement of the rack. During engagement with the rack, a 50 complete rearward movement of the rack against the restoring action of the springs 43 will take place until the last tooth of the group disengages the rack, at which instant the segmented pinion 63 is no longer in engagement with the rack, and the rack is accordingly free to snap back to its 55 normal position in response to the restoring action of the springs 43.

The effect of such movement on the part of the rack is to produce intermittent operation of the spray gun, by reason of the control rod connection from the rack member to the valve control lever 25 of the spray gun. Thus, as the control valve lever is urged toward a valve open position in response to the relatively slow rearward movement of the rack during a period of engagement with the segmented pinion, it will complete its full swing within a small initial portion of the rearward travel of the rack, after which the remainder of such rearward travel merely serves to draw the front end of the control rod 51 70 75

carrying the washer nut combination 55 closer to the valve control lever, bringing about a greater compression of the spring and at the same time holding the valve control lever 25 in full valve open position. Upon the completion of the rearward stroke of the rack, the control rod will snap back to its original position in response to the sudden return movement of the rack, and in this it is aided by the spring 53 at the end of the rod. 10 During the course of such sudden return movement of the control rod, the pressure of the spring 53 tending to hold the valve lever in full open position is released, to be followed by abutment of the nut 57 against the lever, forcing it suddenly from a full open position to a fully closed position, thus bringing about a sharp cutoff of the paint flow from the nozzle of the spray gun.

Thus, it will be apparent that the spray gun will spray paint or lacquer throughout substantially the entire interval that the segmental pinion 63 is in engagement with the rack 41. Inasmuch as such interval is determined by the number of teeth in any one group on the segmented pinion, and the period between such rack engaging intervals is determined by the spacing between the groups of teeth, it will follow that the line formed through operation of the flow control apparatus will be of the interrupted type, and that the character of such interruptions, that is, the pattern created, will be determined by the number of groups of teeth and the number of teeth in each group, and the spacing of such groups about the periphery of the pinion. The ratio of spacing to the peripheral distances occupied by such groups will determine the length of line segments and the spacings therebetween. Without destroying this ratio of line segments to spacings, the linear dimension of both will simultaneously vary with the speed ratio between the guide wheel and the pinion, but will be independent of the speed at which the guide wheel may be caused to rotate.

The number of teeth to a group and the spacings between groups need not be uniform for any particular pinion. A uniform arrangement will give a uniformly interrupted line, whereas departures therefrom will enable the production of lines of many desired patterns.

A number of such flow control apparatus, as has been described, may furthermore be arranged side by side to simultaneously produce a plurality of parallel lines, in which case the pinions may be mounted upon a common shaft and driven through a common clutch.

While I have described a preferred embodiment of my invention in great detail, it is apparent that it is subject to many modifications within the contemplated scope of my invention, and I accordingly do not desire to be limited to any specific detail described, except as may be necessitated by the prior art and the appended claims.

I claim:

1. Apparatus for controlling the flow of liquid from a spray gun moving along a desired path, comprising a spring biased rack for connection to such spray gun, a segmented pinion engageable with said rack and adapted, upon rotation, to periodically move said rack in opposition to the spring bias, and means for driving said segmented

pinion including a guide wheel and a drive connection between said guide wheel and said segmented pinion.

2. Apparatus for controlling the flow of liquid from a spray gun moving along a desired path, comprising a segmented pinion, rotatable in accordance with movement of such spray gun, a toothed member engageable by said segmented pinion during rotation of said pinion to provide intermittent movement of said toothed member and means for effecting connection from said toothed member to said spray gun to control operation thereof in accordance with such intermittent movement of said toothed member.

3. Apparatus for controlling the flow of liquid from a spray gun moving along a desired path, comprising a segmented pinion, rotatable in accordance with movement of such spray gun, a rack engageable by said segmented pinion during rotation of said pinion to provide intermittent movement of said rack, and means for effecting connection from said rack to said spray gun to control operation of said spray gun in accordance with such intermittent movement of said rack.

4. Apparatus for controlling the flow of liquid from a spray gun moving along a desired path, comprising a segmented pinion, a guide wheel in drive connection with said segmented pinion, a toothed member engageable by said segmented pinion during rotation of said pinion to provide intermittent movement of said toothed member, and means for effecting connection from said toothed member to said spray gun to control operation thereof in accordance with such intermittent movement of said toothed member.

5. Apparatus for controlling the flow of liquid from a spray gun or the like comprising a base, a rack supported on said base and capable of reciprocatory movement thereon, means for restricting said rack to such reciprocatory movement, spring means for biasing said rack to one extreme position of its range of movement, a pinion having teeth disposed in groups at intervals about its periphery, means for supporting said pinion in engageable relationship with said rack, said last means having a sprocket thereon for establishing a drive connection to said pinion.

6. Apparatus for controlling the flow of liquid from a spray gun or the like comprising a base, a rack supported on said base and capable of reciprocatory movement thereon, means for restricting said rack to such reciprocatory movement, spring means for biasing said rack to one extreme position of its range of movement, a pinion having teeth disposed in groups at intervals about its periphery, an upright on said base at either side of said rack, a shaft bearing mounted on each of said uprights, said pinion being affixed to a shaft and supported intermediate said uprights in engageable relationship with said rack, by said shaft journaled in said bearings and extending beyond at least one of said bearings, and a one way ratchet clutch having one member affixed to said extending end of the shaft and a complementary member freely mounted thereon and including a sprocket for enabling a drive connection through said clutch to said pinion.

LAWRENCE W. CORNELISON.
